United States Patent Office.

J. H. HOBBS, OF WHEELING, WEST VIRGINIA.

Letters Patent No. 89,996, dated May 11, 1869.

IMPROVED PITCHER.

The Schedule referred to in these Letters Patent and making part of the same.

To all whom it may concern:

Be it known that I, J. H. HOBBS, of Wheeling, in the county of Ohio, and State of West Virginia, have invented a new and useful Improved Pitcher, and I do hereby declare that the following is a full, clear, and exact description of the same, reference being had to the annexed drawing, making part of this specification, in which—

Figure 1 is a side elevation.

Figure 2, a vertical section on line *x x*.

Figure 3, a vertical section on line *y y*.

The same letters in the several figures indicate identical parts.

My invention relates to that class of sirup or punch-pitchers which is made of glass or earthenware, and is covered by a metallic top; and

My improvement consists in forming a part of the top or cover from the material from which the body of the pitcher is made, and also in a more convenient mode of attaching the hinged cover, and also in constructing the body of the pitcher with lugs or projections, to which the metallic sockets of a handle of metal or other suitable material may be attached.

In the annexed drawing—

A is the body of the pitcher, which may be constructed of any desired form, about one-half of the top of the pitcher being covered by the material of which the body is composed, as shown at *a*, leaving an opening on the side adjoining the spout, of about half the area of the top of the pitcher.

The hinged top covers, when closed, this opening, leaving a projecting lip, which covers, also, the spout.

This top is attached to the band *b* by hinges *b'*.

This band *b* fits over the top portion *a* of the pitcher,

and is constructed with bent flanges *b*³, which may be slid forward over the fillet encircling the top, *a*.

The band is also constructed with ears *b*², attached under the hinges, which, when the band is slid forward until the hinges are over the edge of the curved portion *a*, may be bent down under the bevelled edge of the top, *a*, and thus secure the metallic cover in place.

In order that handles may be attached of a different material from that used in constructing the body *A* of the pitcher, the latter is moulded with two projections, *C* and *C'*, as shown, having indentations *c c*, as shown, on opposite sides thereof.

The handle may be made entirely of metal, or it may be of wood, or other suitable material, and have attached thereto metallic sockets, which, receiving the projections *C C'*, may be firmly secured thereto by screws or rivets, which, passing through the metallic sockets, enter the indentations *c c*.

What I claim as my invention, and desire to secure by Letters Patent, is—

As an article of manufacture, a pitcher, having projections *C C'*, to receive the sockets of the handle, a portion of the cover, *a*, formed of the same material with the body, and a hinged cover, *B*, attached thereto, substantially as set forth.

In testimony whereof, I have signed my name to this specification, in the presence of two subscribing witnesses.

J. H. HOBBS.
